CLAIM

The ornamental design for a vest to house the components of a wearable mobile computer, as shown and described.

DESCRIPTION

FIG. 1 is a left side elevational view of a vest to house the components of a wearable mobile computer showing our new design; the broken line shown throughout the views being understood to represent stitching;

FIG. 2 is a right side elevational view thereof;

FIG. 3 is a rear elevational view thereof; and,

FIG. 4 is a front elevational view thereof.
